[57] CLAIM

The ornamental design for a package for a contact lens, as shown and described.

DESCRIPTION

FIG. 1 is a perspective view of a package for a contact lens showing our new design;

FIG. 2 is a left side elevation view thereof; the right side elevational view being a mirror image thereof;

FIG. 3 is a top plan view thereof;

FIG. 4 is a bottom plan view thereof;

FIG. 5 is a front elevational view thereof; and,

FIG. 6 is a rear elevational view thereof.
